[57] CLAIM

The ornamental design for a portable electronic tester and analyzer, substantially as shown and described.

DESCRIPTION

FIG. 1 is a left front perspective view of a portable electronic tester and analyzer showing our new design;

FIG. 2 is a right side elevational view thereof;

FIG. 3 is a top plan view thereof with portions of the cover omitted for ease of illustration;

FIG. 4 is a front elevational view thereof with the cover omitted entirely for ease of illustration;

FIG. 5 is a top plan view thereof with the cover in a closed position;

FIG. 6 is a rear elevational view thereof with the cover in a closed position.

FIG. 1.

FIG. 2.

*FIG. 3.**FIG. 4.**FIG. 5**FIG. 6.*
